UNITED STATES PATENT OFFICE.

OLIVER J. WILLIAMS, OF BURLINGAME, CALIFORNIA, ASSIGNOR TO WILLIAMS PATENT CRUSHER & PULVERIZER CO., OF ST. LOUIS, MISSOURI, A CORPORATION OF MISSOURI.

CRUSHER.

1,322,211.

Specification of Letters Patent. Patented Nov. 18, 1919.

Application filed October 14, 1918. Serial No. 258,058.

To all whom it may concern:

Be it known that I, OLIVER J. WILLIAMS, a citizen of the United States, residing at Burlingame, in the county of San Mateo 5 and State of California, have invented certain new and useful Improvements in Crushers, of which the following is a specification.

This invention relates to certain new and 10 useful improvements in crushers, and like machines having a rotor and pivoted hammers mounted on hammer rods.

The object of my invention is to provide 15 means for readily mounting and removing the said hammers, and the peculiarities thereof will be hereinafter described and claimed.

In the manufacture of crushers and like machines comprising a suitable casing and 20 a rotor having pivoted hammers, the hammer rods forming the pivot for the hammers, pass through disks mounted on a shaft and alternating with the hammers. A flywheel and pulley on opposite ends of the 25 shaft outside the bearings interfere with the removal of the hammer rods, when the rotor is longer than the space intervening between the flywheel and pulley respectively, and the adjacent end of the rotor when the 30 cover of the casing is raised either the removal of flywheel or pulley is necessary or some other means must be provided, to allow of taking out the rods in such a case. Frequent change of hammers for redressing the 35 points or for replacement, calls for means to facilitate withdrawing said hammer rods, which I will now describe in connection with the accompanying drawing on which like reference letters indicate corresponding 40 parts, and in which Figure 1 represents a perspective view of a rotary shaft, with pulley and flywheel fan, on the outer ends, and a rotor in the middle embodying my invention; Fig. 2, a longitudinal section of part 45 of a suitable casing and a rotor similar to that shown in Fig. 1 mounted therein; and Fig. 3, an end view of such a rotor.

The letter A designates a suitable casing, with a cover B adapted to be lifted as indi-

cated by dotted lines from a rotary shaft C, 50 mounted in suitable bearings D, and having at one end a pulley E, and at the other end a flywheel F that may carry a fan G as in Fig. 1. On said shaft and within the casing, are mounted a set of disks H, carrying alternating pivoted hammers I by means of hammer rods in sections J that pass through registering openings in said disks and hammers, and meet at the central, or other intermediate disk H'. This rod 60 section J is shown flush with the outside of the end disk, and a plate ring K is fastened 65 by capscrews L, or otherwise, detachably to the outer face of said end disk, to serve as a keeper to prevent said rod J from shifting in said disks. A hole k Fig. 3 in said plate is adapted, by rotating the plate, to register successively with the hammer rods, to allow of their withdrawal when hammers are to be renewed and a tapped hole M in 70 the outer end of rod J, allows of screwing in the end of a bolt for pulling out said rod. Fig. 2 shows in dashed lines, a section of hammer rod pulled out into the intervening space over the bearing between the flywheel and rotor. The hammer rods are 75 divided into such lengths of section as correspond with and are less than, said intervening space.

I claim:

In a device of the character described comprising a shaft, a set of disks having registering holes, and hammer rods mounted in said holes, a cover plate rotatably mounted on the outer face of the set of disks 85 and normally covering the ends of said rods and having a hole adapted to register successively with said rods by rotated adjustment of said plate to allow withdrawal of each rod, and means to secure the plate 90 in its normal closing position, and allow of rotating it to register said hole with said rods successively when it is desired to withdraw said rods; substantially as described.

In testimony whereof I have affixed my 95 signature.

OLIVER J. WILLIAMS.
